UNITED STATES PATENT OFFICE.

PAUL SIMON, OF PERTH AMBOY, NEW JERSEY.

LIFE-SAVING SUIT.

1,147,274.

Specification of Letters Patent. Patented July 20, 1915.

Application filed January 9, 1915. Serial No. 1,333.

To all whom it may concern:

Be it known that I, PAUL SIMON, a subject of the King of Hungary, residing at Perth Amboy, in the county of Middlesex and State of New Jersey, have invented new and useful Improvements in Life-Saving Suits, of which the following is a specification.

My invention relates to a life saving suit particularly designed for travelers on board of steamers or other water-craft and has as its principal object to provide a device suitable for constant wear and ready for immediate use in case of emergencies, saving the wearer from drowning in the water and from exposure to the direct contact with it.

In the accompanying drawing: Figure 1 is a front elevational view of my device, some parts broken away, showing the device in its state of ordinary wear. Fig. 2 is a side elevational view of my entire device, on a slightly reduced scale, showing it in an inflated state, as ready for use in an emergency case.

The same part is designated by the same reference characters throughout the several views.

Referring more particularly to the drawing, 3 is a suit made of watertight material, having pockets or bags 4 and 5 made of airtight material, preferably rubberized silk, attached to it, one at the front part and one at the back portion of the suit, communicating with each other on either side by means of channels 6 made of the same material, and two similar pockets or bags 7, one on each trouser-leg beneath the knee-portions thereof, communicating with the pockets 4 and 5 through channels 8 formed on either side of the suit also of the same material as the pockets.

On the pocket 4 at the front portion of the suit I provide an air valve 9 of the type usual in air-cushions, operated by a turn of one thumb and finger and attached to it a flexible tube 10 of sufficient length to reach to the mouth of the wearer of the suit. Two small straps 11 are provided on the same pocket to take up the free end of the tube 10 when not used.

The suit has short sleeves 12 and is buttoned at the shoulder-portions 13. There are rubber soles 14 attached to the lower ex-

tremities of the trousers by means of watertight seams.

55

A person may wear this suit aboard any ship without great inconvenience and in case of an accident necessitating its use he has simply to inflate the pockets through the tube, all pockets filling simultaneously on account of the channels of communication. The inflating can be performed in one minute and the air valve being then closed and the free end of the tube stowed away in the straps, the person is kept afloat by the 65 pockets indefinitely in as convenient a position as possible under the circumstances, the lower pockets causing the person practically to sit in the water. The whole suit being watertight and the neck and shoulder portions well out of water, the inconvenience of the direct contact of the body with the water is also eliminated.

70

If, in case of a continued stay in the water, any air should escape from the pockets, 75 they may easily be refilled in an obvious manner.

If a person wishes to sacrifice the convenience of preventing direct contact of the body with the water, in case of accident, 80 to more commodity in ordinary circumstances, the part of the suit below the waist may be dispensed with and the suit, in the form of a blouse, having only the breast- and back-pockets, made fast around the 85 waist in any convenient manner. In this form of my invention there would of course be no outlets from the pockets, but they would only communicate with one another.

It is understood that while I have thus 90 shown and described the preferred forms of my invention, I do not want to be limited to its mechanical details and may resort to such alterations and modifications as come within the scope of the claim hereunto appended.

95

Having thus described my invention, what I claim is:

A life-saving suit made of watertight material in the shape of a union suit, enveloping the whole body except the head, neck and part of the arms, buttoned at the shoulder portions and terminating in rubber soles, 100 said suit comprising, in combination, airtight pockets one at the front part, one at the back and one each on the trouser legs, 105

beneath the knee-portions thereof, all of
said pockets connected with each other by
airtight channels made of the same ma-
terial as the pockets, the front-pocket pro-
vided with an air-valve and a flexible tube
attached to it, said flexible tube being of
sufficient length to reach to the mouth of
the wearer of the suit, adapted to inflate

therethrough said pockets and said air-valve
adapted to be opened or closed by a turn ¹⁰
with one thumb and finger.

PAUL SIMON.
